(57) **CLAIM**

The ornamental design for a ultrasonic mosquito repellent, as shown and described.

DESCRIPTION

FIG. 1 is a front perspective view of a ultrasonic mosquito repellent design showing my new design.

FIG. 2 is a front view of a ultrasonic mosquito repellent.

FIG. 3 is a rear view of a ultrasonic mosquito repellent.

FIG. 4 is a left side view of a ultrasonic mosquito repellent.

FIG. 5 is a right side view of a ultrasonic mosquito repellent.

FIG. 6 is a top view of a ultrasonic mosquito repellent.

FIG. 7 is a bottom view of a ultrasonic mosquito repellent; and,

FIG. 8 is a rear perspective view of a ultrasonic mosquito repellent.

The broken lines in the drawings depict portions of the ultrasonic mosquito repellent that form no part of the claimed design.
